UNITED STATES PATENT OFFICE

ALFRED C. SLOAN, OF PHILADELPHIA, PENNSYLVANIA

VIBRATORY DEVICE FOR DENTAL MOLDING MACHINES

Application filed May 29, 1923, Serial No. 642,352. Renewed August 2, 1929.

My invention relates to a novel vibratory device, primarily intended for use in connection with dental molding machines, and has particular relation to a parent application 5 of such character filed by me June 24, 1920, and given Serial No. 391,414.

The principal object of my invention resides in providing novel means for effecting the vibration of a vibratory device, said 10 means being adjustable to secure the desired degree of vibration to the said vibratory device.

A further object of my invention is to provide a vibratory device of this character 15 which consists of an adjustable balancing means carried on the rotor shaft of an electric motor yieldingly supported from a base member, means whereby said balancing means may be adjusted to unbalance said 20 rotor shaft to effect the vibration of said motor in the operation thereof.

A still further object of my invention consists in yieldingly supporting a motor from 25 a stationary base member, the rotor shaft of said motor being provided with balancing means, said means consisting of a disc being fixed to and eccentrically supported on said shaft, a second disc carried by said first-mentioned disc and eccentric in respect thereto, 30 means for adjusting said discs in relation to each other, and means adapted to hold said discs as a unitary mass in the operation of the device.

Furthermore, the device comprises broadly, a vibratory device adapted for use with dental molding machines, wherein a motor is secured to and suspended from the under-surface of a molding platform, said platform being yieldingly supported from a base 40 member, the rotor shaft of said motor being provided with balancing means, which consists of a disc secured to said rotor shaft, the axis of said disc being eccentric with respect to the axis of the rotor shaft, a second disc 45 rotatably adjustable on said first-mentioned

disc to change the eccentric relation of the axis of said discs, means for holding said discs against turning and longitudinal movement in respect to each other.

Other novel details of construction and advantages of my device are brought out in the following description, when read in conjunction with the accompanying drawings, in which Fig. 1 represents a vertical longitudinal sectional view illustrating one embodiment of my invention; Fig. 2 represents a top plan view of Fig. 1; Fig. 3 represents a vertical transverse sectional view taken on the line 3—3 of Fig. 1; Fig. 4 represents an enlarged fragmentary sectional view partly in elevation taken on the line 4—4 of Fig. 3, showing an embodiment of balancing means for the rotor shaft of the motor; and Figs. 5, 6 and 7 represent sectional views showing the several steps in the production of the positive 65 model of the mouth from which the denture, either vulcanite or metallic, is produced.

Referring to the drawings, 1 designates a base member or support on which the device is supported, the base member having secured 70 to its upper face the upright posts 2, which are provided at the upper portions with collars 3 and 4, spaced apart and secured to said posts. 5 and 6 designate coil-springs encompassing said posts 2 with the outer ends 75 thereof respectively engaging against the inner or opposed faces of the collars 3 and 4, while the inner ends of the said springs 5 and 6 engage the opposite faces of brackets 7 of a framework 8, which carries the molding board or platform 9.

Each of the brackets 7 has a vertical opening 10 therethrough, through which the respective posts 2 extend, to allow for the vertical yielding movement of the frame 8 and platform 9 with respect to the posts 2 secured to the base member 1. The platform 9 may be formed with depressed portions 11 and 11^a 85 to form trays for the molds or to contain a plastic material preparatory to using the 90

same. The platform 9 is preferably provided with the aproned portion 12 to cover the mechanism of the device.

To effect an even distribution of the vibration over the entire platform, I preferably arrange the yielding means adjacent to the four corners of the platform as illustrated in Fig. 2 of the drawings.

To effect vibration of the platform 9, I provide a novel vibratory device carried on the under portion of the platform, this vibratory device consists of a motor 13 preferably electrically driven, which is suspended from and secured to the frame 8 at a location intermediate the four posts 2 on which the platform is yieldingly supported. The motor 13 is provided with a rotor shaft of the usual type and in this construction the rotor shaft is preferably supported on roller bearings (not shown) located in the ends of the motor housing. 14 designates as an entirely adjustable balancing means carried on the end of the rotor shaft, the said balancing means consisting of a disc 15 eccentrically mounted and secured to the rotor shaft. This disc on its peripheral face is grooved at 16 as shown in Figs. 3 and 4, the purpose of which will be described later on in the description. 17 designates a second disc having an opening 18 therethrough, said opening being located eccentric to the axis of said disc.

The assembly of the disc 17 to the disc 15 consists in positioning the disc 15 in the opening 18. The disc 17 is provided with setting screws 19 which engage the bottom of the groove 17 to hold said disc 17 in a fixed relation to the disc 15. To effect adjustment of the discs in relation to each other, the setting screws 19 are screwed out of engagement with the disc 15, without entirely moving the end of the screws out of the groove, the ends of the screws preventing longitudinal displacement of the disc 17 with respect to the disc 15, at the same time allowing for the turning of the disc 17 on the disc 15 to alter the eccentricity of the axis of said discs in relation to each other, and to the axis of the rotor shaft on which the disc 15 is carried.

Referring to Figs. 5, 6 and 7 of the drawings, I have shown for purpose of clearness several steps in the method of producing a positive model of the mouth. In Fig. 5 is shown the ordinary type of dental impression mold 21 or negative mold taken from the mouth. It is from this wax impression or mold that the positive model of plastic material is molded. (See Fig. 6 of the drawings wherein the plastic material to form the positive model is shown in the impression mold at 22). In Fig. 7 is shown the positive model of the mouth from which the denture is made, the same being removed from the wax impression 21.

In the operation of my novel invention in connection with the above referred to method

to produce the positive model of the mouth or plastic material, the operator secures one or more of the mouth-trays containing the wax impression molds to the top of the platform 9 in the tray portion 11 thereof in any desirable manner, as for instance by wax as illustrated in Figs. 5 and 6 of the drawings. The tray portion 11^a contains plaster of Paris which has been mixed to a proper consistency preparatory to using the same for molding purposes, the continuous vibration of the platform keeping the plastic material at the proper consistency. Continuing the vibration of the platform, the plastic material is applied in said negative mold, the uniform vibration thereof eliminating the air bubbles from the plastic material to effect a positive setting of the plastic material in the negative wax impression mold, the result being a more perfect positive model of the mouth than has heretofore been produced.

It will readily be seen from the description and reference to Figs. 3 and 4 of the drawings that the balancing means 14 on the rotor shaft of the motor may be adjusted to secure the proper degree of vibration for the yielding platform 9 from which the vibratory device is supported, the adjustment of the discs 15 and 17 in respect to each other effecting unbalance of the rotor shaft which is imparted to the motor, hence to the molding platform in the operation of the device.

Having thus described my invention, what I claim and desire to protect by Letters Patent of the United States is:—

1. A vibratory device of the character described, which comprises a stationary base member, a motor having a rotor shaft yieldingly supported on said base member, means carried on the rotor shaft of said motor to effect the unbalance of said shaft in the operation of the motor.

2. A vibratory device of the character described, which comprises a stationary base member, a motor having a rotor shaft yieldingly supported on said base member, balancing means carried on the rotor shaft of said motor, and means for adjusting said balancing means to effect the desired degree of unbalance of said rotor shaft.

3. A vibratory device for dental molding machines, which comprises in combination, a base member, posts secured to said base, a platform yieldingly supported on said posts and said platform, a motor suspended from and supported by the underneath portion of said platform, said motor being provided with a motor shaft, discs carried on said motor shaft, the axes of said discs being eccentric with respect to each other and with the axis of the motor shaft, means for adjusting the eccentric relationship of said discs, and means for holding said discs as a unitary mass.

4. A vibratory device of the character de-

- scribed, which comprises a stationary base member, a molding platform vibratory with respect to said stationary base member, a motor having a rotor shaft fixedly carried by said molding platform, balancing means carried on the rotor shaft of said motor, and means for adjusting said balancing means to effect the desired degree of unbalance of said rotor shaft.
- 10 5. A vibratory device of the character described which comprises a stationary base member, a molding platform, a motor having a rotor shaft fixedly carried by said molding platform, said platform and motor yielding-
15 ly supported on said base member, a disc secured to said rotor shaft and eccentric thereto, a second disc on said first-mentioned disc and eccentric thereto, means for adjusting the eccentricity of the axis of said discs
20 with respect to each other, and means for holding said discs as a unitary mass.
6. A vibratory device of the character described which comprises in combination, a base member and a vibratory molding plat-
25 form, a motor having a rotor shaft fixedly secured to said molding platform and yield-
ingly supported on said base member, said base member stationary with respect to said vibratory molding platform.
- 30 7. A vibratory device of the character de-
scribed which comprises a stationary base member, a molding platform, a motor having a rotor shaft fixedly carried by said mold-
35 ing platform, said platform and motor
yieldingly supported on said base member, a disc carried by and secured to said rotor shaft, a second disc, means for altering the eccentricity of the axis of said discs in relation to each other, and means for holding
40 said discs as a unitary mass on said rotor shaft.
8. A vibratory device of the character de-
scribed which comprises a molding platform rectangular shaped in plan, supporting
45 means for said molding platform, means for yieldingly connecting said molding platform adjacent its four corners with said supporting means, and means intermediate said supporting means for imparting a vibratory
50 movement to said molding platform.
9. A vibratory device of the character de-
scribed which comprises a molding platform consisting of a rectangular shaped molding board proper and a framework situated be-
55 low said molding board and in parallel rela-
tion thereto, stationary posts arranged adja-
cent the four corners of said molding board and movably positioned in said framework, means for yieldingly supporting said frame-
60 work on said posts, vibratory means inter-
mediate said stationary posts carried by said framework to impart vibration to said mold-
ing board.
10. A vibratory device of the character de-
65 scribed which comprises a molding platform
- consisting of a molding board proper and a framework situated below said molding board proper, said framework yieldingly supported on stationary posts, a motor hav-
70 ing a rotor shaft fixedly carried by said framework, balancing means carried on the rotor shaft of said motor and means for ad-
justing said balancing means to effect the de-
sired degree of unbalance of said rotor shaft.
- In testimony whereof, I have affixed my
75 signature.
